EMULSION TREATING APPARATUS

William S. McCraw, New London, Conn.; Laura Peck McCraw, executrix of said William S. McCraw, deceased

Application March 22, 1950, Serial No. 151,177

10 Claims. (Cl. 204—304)

1

In a gas manufacturing plant, the gas is delivered for storage to a tank open at the bottom and floating in a well containing liquid. The liquid is initially water, but after a period of operation the liquid includes a considerable amount of tar. When the raw gas is delivered to the interior of the tank it contains a considerable amount of water and tar in suspension. The suspended water and tar condense out of the gas and mingle with the water in the well. As the result of the deposit of water and tar from the gas, and as the result of pumped-in tar and water from other plant equipment, and also as the result of rainfall, the amount of liquid in the well increases and an overflow pipe is provided for the discharge of any liquid rising above the overflow pipe level.

Some of the tar deposited in the liquid in the well settles and accumulates in a layer at the bottom of the well. This tar presents no particular problem as it can be pumped out from time to time and used as a fuel or otherwise. Above the bottom layer of tar, there may be a layer of tar-in-water emulsion which is heavier than water. The tar in this emulsion is in the process of settling out and it gradually merges with the layer of tar at the bottom. However, some of the tar, instead of gradually settling to the bottom, becomes emulsified with the water to form a water-in-tar emulsion which is lighter than water and which collects as a floating layer at the top. The water-in-tar emulsion has a water content far greater than the tar content. Between the layer of tar-in-water emulsion near the tar at the bottom and the layer of water-in-tar emulsion at the top there may be a layer of relatively clean water or liquor.

The floating water-in-tar emulsion presents serious disposal problems. It is this emulsion that is discharged through the overflow pipe to conventional separating equipment which is designed to settle out tar from tar-in-water emulsion but which will pass the water-in-tar emulsion. The last said emulsion goes along with the water and fouls up the filter equipment which is provided to remove the slight traces of oil left in the water before disposal to sewers, streams or rivers.

If the water-in-tar emulsion is drawn from the holder tank to keep the overflow level at the proper point, it is not useful as a fuel nor for any other purpose due to the high water content. By reason of sanitary regulations it cannot be discharged to sewers and by reason of pollution regulations it cannot be discharged to rivers or other streams.

To conform with these regulations, valves are placed in the overflow pipes of the holder tanks to hold back the floating emulsion. This raises the level of the liquid to such an extent that the

2

gas mains to and from the holders are flooded with the water-in-tar emulsion and gas flow is retarded or shut off. The emulsion being very viscous, the problem of removal is considerable, and when drains or power pumps provided for the removal of ordinary amounts of condensate fail in their duty, hand pumping is frequently necessary. All of these problems represent extra work and expense.

10 For convenience the floating layer is herein referred to as a water-in-tar emulsion, which it primarily is. Actually, however, the composition of the floating layer is usually much more complex. The said layer may include gases such as carbon dioxide, and liquids such as oil, water and tar, and solids such as lampblack.

15 The general object of the present invention is to provide an apparatus for treating the troublesome water-in-tar emulsion so as to substantially completely separate the tar from the water. After separation, the tar and the water can be separately disposed of in any usual or suitable manner. Generally speaking, an emulsion treater embodying the invention provides an effective, inexpensive and continuously acting means for immediately handling the emulsion and for eliminating the problems. While reference has been made to the treatment of the water-in-tar emulsion floating in a layer at the top of the liquid in

20 a well, it will be understood that an apparatus embodying the invention is not necessarily so limited and that the said apparatus can be used for the treatment of the same or similar emulsions wherever encountered.

25 30 35 Other and more specific objects of the invention will be apparent from the drawings and from the following description and claims.

The accompanying drawings show alternative embodiments of the invention, but it will be understood that various changes may be made from the constructions shown, and that the drawings are not to be construed as defining or limiting the scope of the invention, the claims forming a part of this specification being relied upon for that purpose.

40 45 Of the drawings:

Fig. 1 is a view partly in section and partly diagrammatic showing an apparatus embodying the invention.

50 55 Fig. 2 is a view showing an alternative embodiment of the invention, the right portion of this view showing some of the same parts as shown in the left portion of Fig. 1.

Fig. 3 is a view showing another alternative embodiment of the invention.

Referring to the drawings and more particularly to Fig. 1 thereof, 10 and 12 represent the upper and lower portions of a gas tank floating in a well 14 having a top platform 16. These parts are or may be of standard construction and the

fragmentary showing of them is intended to be merely schematic. There is an annular space between the outer walls of the tank parts and the inner wall of the well, and a portion of the before-mentioned floating layer of water-in-tan emulsion is in this annular space, as indicated at E.

The treater for the emulsion E comprises a housing 18 located above the level of the platform 16 and having a preferably horizontal cylindrical chamber therein. As shown, the housing 18 comprises a longitudinal series of tubular or annular members, these including an annular member 20 which may be casting, a tube 22, having a threaded connection with the annular member 20, a tube 24 having a flanged connection with the tube 22, and an annular member 26 which may be a casting having a threaded connection with the tube 24. The housing is closed at its ends by an end plate 28 having threaded engagement with the annular member 20 and an end plate 30 having threaded engagement with the annular member 26.

The emulsion E to be treated is supplied to the cylindrical chamber near the right or entrance end thereof through a pipe 32 which is preferably vertical. As shown, the lower end of the pipe extends into the layer of emulsion E and the upper end of the pipe is threaded into an opening in the bottom of the annular member 20. The components of the emulsion after treatment are withdrawn from the cylindrical chamber near the left or discharge end thereof through an outlet pipe 34. The pipe 34 is shown as being vertical with the lower end thereof threaded into an opening in the top of the annular member 26.

A suitable means is provided for causing the liquid, which is initially an emulsion, to flow through the supply pipe 32 and through the main chamber and through the outlet pipe 34. This means is preferably connected with the outlet pipe 34 and acts by suction. As shown, the upper end of the pipe 34 communicates with a suitable suction means which may be a steam siphon indicated generally at 36. The steam siphon as shown has a main body 38 with chambers 40 and 42 therein separated by a wall 44. The pipe 34 communicates with the chamber 40 and the chamber 42 communicates with a discharge pipe 46. Mounted in an opening in the wall 44 is a tube 48 having a diverging conical wall 50 in the chamber 40. A steam nozzle 52 is provided which receives steam from a supply pipe 54. The end of the nozzle 52 is within the conical portion 50 of the tube 48.

When steam under pressure is delivered through nozzle 52, the vacuum created draws liquid into the chamber 40, and through tube 48, where condensation of the steam occurs. The steam at this time imparts enough energy to the liquid, due to the velocity derived from the steam expansion and subsequent condensation, to carry it through tube 48 and to build up considerable discharge pressure. There is thus a continuous flow of liquid from the emulsion layer E to and through the discharge pipe 46.

The main housing 18 constitutes an outer electrode as will be explained, and it is formed of a suitable metal such as iron or steel. An inner centrally located metallic electrode 56 is provided within the chamber of the housing or electrode 18, this inner electrode extending longitudinally. When the chamber in the outer electrode is horizontal, the inner electrode is also horizontal. For reasons to be hereafter more

fully set forth, the inner electrode 56 preferably has different diameters at different positions along its length, the diameters being successively smaller in the direction of liquid flow. Preferably the inner electrode is adjustable as to length.

The inner electrode 56 may be widely varied as to details of construction, but as shown in Fig. 1 it comprises three telescopically engaging tubes 58, 60 and 62 of suitable metal which may be iron. Preferably the tubes 58 and 60 are in fixed relative positions, being connected by welding at 63. The inner tube 62 of the inner electrode has a slip fit with the tube 60 and is telescopically movable longitudinally relatively thereto. The inner electrode preferably also comprises a ring 64 carried by the largest tube 58 at the right end thereof. The ring 64 is preferably formed of a highly conductive metal such as copper. The electrode has its largest diameter at the ring 64 and has successively smaller diameters at the tube 58, at the tube 60 and at the tube 62.

A generally cylindrical member 65 of insulating material enters and closes the right end of the outer or largest tube 58. A second insulating member 66 is provided adjacent the member 65, the two members being connected by screws 68, 69. The members 65 and 66 are recessed to provide a central chamber 70, and a suitable packing or gasket is provided between the members 65 and 66 to exclude liquid from the said chamber. The member 65 has a central aperture, and a conducting rod 72 extends through and fits this aperture, being provided with a head within the chamber 70. One or more radial screws 74 extend through apertures in the tube 58 and in the insulating member 65, these screws serving to mechanically connect the tube 58 with the member 65 and also serving to provide an electrical connection between the said conducting rod 72 and the said tube 58.

A tubing connector 75 is threaded into the central aperture in the insulating member 66, a liquid-tight joint being provided. A longitudinal tube 76 is provided having a flared inner end, the flared end of the tube engaging the connector 75 and being held in place by a threaded sleeve 78. The tube 76 extends through a central aperture in the end plate 28, a liquid-tight connection being provided by a gland 80. An insulated conductor 82 extends through the tube 76 and is connected at its inner end with the head of the conducting rod 72. It will be seen that an electrical connection is established from the conductor 82 through the rod 72, through the screws 74, and through the electrode parts 64, 58, 60 and 62.

Suitable insulating means are provided for supporting the inner electrode 56 in a central position within the chamber in the outer electrode 18. The tube 58 is provided with three or more insulating buttons 84, 84 and the tube 60 is provided with three or more insulating buttons 86, 86. The buttons 84, 84 and 86, 86 are attached by screws, and plugs of insulating material are preferably provided for closing the outer ends of the holes for the screws. The several buttons engage with the interior face of the tube 24.

During assembly the tubes 58 and 60 of the inner electrode are longitudinally movable with respect to the outer electrode 18 and they can be variously positioned in accordance with anticipated conditions. In order to definitely locate the tubes 58 and 60 and to prevent any possible

movement thereof toward the left, a ring 88 of insulating material is secured to the tube 24 in position to engage the buttons 86, 86.

As has been stated, the inner electrode is preferably adjustable as to length. The adjustment as to length may be variously effected, but when the electrode comprises a plurality of tubes, the adjustment is effected by longitudinally moving one tube relatively to another. As shown, it is the inner tube 62 which is longitudinally movable, this tube being so movable relatively to the tubes 60 and 58.

A suitable means is provided for longitudinally moving the tube 62. At the left end of the said tube is a plate 90 having a central stud at its left side. A coil tension spring 92 is located within the tube 62, this spring being connected at its left end with the plate 90 and being connected at its right end with a member 94 having threaded engagement with the conducting rod 72. The spring 92 tends to hold the tube 62 in its position at the right as shown by full lines in Fig. 1. The spring 92 also serves to provide an additional electrical connection between the rod 72 and the tube 62.

For telescopically moving the tube 62 toward the left in opposition to the spring 92, there is provided a centrally located longitudinal pull rod 96. The rod 96 extends through an aperture in a member 98 threaded into an opening in the left end plate 30, and the said rod is connected with the stud on the plate 90 by means of an insulating connection 100. A gland 102 insures a liquid-tight connection between the rod 96 and the member 98. At the left end of the rod 96 and having threaded connection therewith is a handle 104, by means of which the rod can be moved longitudinally to correspondingly move the electrode tube 62. The tube is moved toward the left in opposition to the spring 92, and can be permitted to move toward the right by the action of the said spring. A set screw 106 can be engaged with the rod 96 to lock the rod and the tube in any position of adjustment. The full lines show the tube in its extreme position toward the right and the dotted lines show the tube in its extreme position toward the left.

It will be seen that all liquid flowing through the main chamber and between the electrodes must pass through the annular space between the outer face of the ring 64 and the inner face of the tube 22. A suitable means is provided for changing the thickness of the annular layer of material at the ring 64 and for changing the rate of flow. For this purpose a tubular member or annulus is provided which is longitudinally movable, this annulus engaging one of the electrodes. As shown, there is an annulus 110 which engages and fits within the tube 22 which forms a part of the outer electrode. The annulus 110 preferably has a conical inner face, the diameter increasing toward the left. The annulus 110 is slotted and is provided with a rack 112 meshing with a pinion 114. The pinion may be turned by a knob 116, to adjust the annulus 110 longitudinally. The annulus 110 may be locked in adjusted position by a set screw 118. By longitudinally adjusting the annulus 110, the thickness of the annular space around the ring 64 may be changed, the thickness of the annular liquid layer and the rate of liquid flow being thus regulated.

Means is provided for establishing an electrical circuit which includes the outer electrode 18 and the inner electrode 56, the current passing

through the liquid which flows in the annular space between the electrodes. Preferably an alternating current circuit is provided and as shown there are two main power leads 120 and 122 which are connected with a suitable source of alternating current. The leads 120 and 122 are connected with a transformer 124 from which extend leads 126 and 128, controlled by a switch 130. The leads 126 and 128 are fused at 132 and 134 and a telltale pilot lamp 136 is connected between the leads. The lead 126 is grounded and is connected with the outer electrode at 138. The lead 128 is connected through a variable choke coil 140 and an ammeter 142 with the before-mentioned conductor 82. The choke coil 140 serves to limit the total amount of current so that it does not exceed the capacity of the fuses at 132 and 134. The choke coil is manually adjustable to control the current flow by increasing or decreasing the inductance as required.

The liquid passing along the annular space between the outer electrode 18 and the inner electrode 56 initially comprises the normally stable water-in-tar emulsion E. The emulsion is ordinarily conductive to a sufficient extent to enable it to allow current to flow between the outer and inner electrodes. As the current flows through the emulsion, the emulsion is acted upon so that the water is released from the tar enveloping it, there being a neutralization of the electrical forces holding the emulsion stable. The resultant mixture of tar and water is quite liquid and is in such condition as to promote separation of the two by subsequent settling out of the tar from the water after discharge through the pipe 46.

It has been found satisfactory to provide between the electrodes 60 cycle current up to about 50 amperes at 110 volts. However, the invention is not so limited, and the character and amount of the current may be widely varied.

The emulsion E is broken down progressively as it moves longitudinally between the electrodes. A relatively large proportion of the emulsion breaking action takes place in the relatively narrow and relatively thin annular space surrounding the conducting ring 64. After partial breaking of the emulsion, successively longer paths of current therethrough are necessary or at least highly desirable. It is for this reason that the inner electrode has successively smaller diameters in the direction of liquid flow. The electrode has its largest diameter at the ring 64 and has successively smaller diameters at the tube 58, at the tube 60 and at the tube 62.

There are several variable factors affecting the action of the described emulsion treater. These factors include variations in the character of the emulsion, variations in the temperature and variations in the rate of flow. The electrical resistance offered by the emulsion which is in part dielectric varies substantially with the aforesaid factors. In order that the total amperage may be maintained approximately at a predetermined optimum amount, the inner electrode is adjustable in length and therefore in area. As shown in Fig. 1, the adjustment in length is effected by longitudinally moving the tube 62 in the manner previously described. It will be obvious that, if the emulsion resistance were not subject to variation, the total resistance of the circuit would vary directly with the length of the adjustable inner electrode. However, the emulsion resistance is subject to variation and compensation for such variation is effected by changing the

length and area of the inner electrode. In practice the operator observes the amperage as indicated by the ammeter 142 and if it is above or below the optimum the handle 104 is moved to correspondingly move the tube 62 and thus restore the amperage to the optimum. The current flow can be alternatively or additionally controlled by the manually adjustable choke coil 140 as previously described.

Preferably, a recirculation duct 144 is provided for returning a portion of the treated liquid from the discharge end portion of the main chamber to the entrance end portion thereof. In the particular construction shown, the recirculation pipe is connected with the outlet pipe 34 rather than directly with the main chamber. The duct 144 comprises a series of pipes connecting the chamber 42 of the steam siphon with the interior of the main chamber at the right or entrance end thereof, preferably separately from the supply pipe 32. In order to assure flow of liquid through the duct 144, one end of the said duct is connected at the forward or discharge side of the liquid moving means such as the siphon 36 and the other end of the said duct is connected at the rearward or intake side of the said liquid moving means and near the entrance end of the chamber in the housing 18. A control valve 146 is included in the duct 144. When the valve 146 is opened some of the mixture, instead of being discharged through the pipe 46, is returned through the duct 144 to the entrance end of the main chamber, being thus recirculated.

The mixture returned through the duct 144 consists chiefly of water which is an electrolyte, the water having relatively small amounts of tar suspended therein. This water, when commingled with the raw emulsion, greatly facilitates the electrolytic action required to cause enough current to flow to break down the emulsion.

The use of a steam siphon as the suction means may have particular advantages. In the event that any residue of the water-in-tar emulsion remains after the action of the electric current, such residue may be changed by action of the steam siphon from a water-in-tar emulsion to a tar-in-water emulsion. This change is or may be caused by the subjection of the emulsion successively to partial vacuum, to heating, to increased velocity and increased pressure, and finally by the introduction into the emulsion of condensed steam globules, the electrical charges of which cancel out or otherwise affect the stabilizing charges of the emulsion components.

It is frequently necessary or at least desirable to raise the temperature of the emulsion before it passes through the annular space between the electrodes, this being particularly important in cold weather or when the emulsion is viscous or gelled. The heating of the emulsion before treating may be effected by heating the mixture returned through the recirculation duct 144. The returned heated mixture is commingled with the raw emulsion entering through the pipe 32. The result is that there is a substantial increase in the temperature of the liquid passing between the electrodes. This increased temperature increases the effectiveness of the electrolytic action. When the suction means is a steam siphon as shown in Fig. 1, the steam serves to heat the returned mixture and no separate heating means is necessary.

Reference has been made to the fact that the emulsion may be gelled. A gelled emulsion is more viscous than an ungelled emulsion and therefore flows less freely through the treater.

However, the gel is more easily broken down by the electrolytic action. This is due to the fact that the gel contains electrolytic liquor which is squeezed out by syneresis and which enables the current to pass more readily than in the usual water-in-tar emulsion. The tendency of the emulsion to gel is therefore advantageous, in that it initiates the flow of current under conditions which would otherwise be unfavorable.

Under some conditions, the emulsion is not sufficiently conductive for satisfactory treatment. When such conditions are encountered a suitable chemical, preferably in liquid form, is introduced into the entrance end portion of the cylindrical chamber to increase the conductivity. For introducing the chemical a container 148 is provided which is preferably connected with the recirculation duct 144, a valve or cock 150 being provided to control the flow from the container to the duct.

Fig. 2 shows an alternative embodiment of the invention which includes means for automatically changing the length of the inner electrode. In this view most of the parts at the right are the same as those shown in the left portion of Fig. 1, but the tube 62 is shown at its extreme left position.

In lieu of the rod 96 there is provided a similar rod 152 formed of brass or other non-magnetic material. Connected with the rod 152 at the left or outer end thereof is a core 154 formed of soft iron or other magnetic material. A counterweight 156 is connected with the core 154 by means of a cord or cable 158. The weight of the counterweight 156 is such that it exerts a force on the core 154 which is slightly greater than the force exerted by the spring 92. Thus the counterweight tends to hold the parts in the positions shown in Fig. 2.

A magnetic coil or winding 160 is provided which surrounds the path of movement of the rod 152 and the core 154, the said rod and core being freely movable through the coil. By means of conductors 162 and 164 the coil 160 is connected in the circuit between the ammeter 142 and the conductor 82.

When the electrode tube 62 is in its fully extended position as shown, the electrical resistance through the emulsion is at the minimum and the amperage in the circuit is at the maximum. Current at maximum amperage passes through the coil 160, which acts to move the core 154 toward the right in opposition to the counterweight 156, such movement being assisted by the spring 92. The tube 62 moves with the core 154, thus increasing the resistance in the circuit and reducing the amperage in the coil 160. As movement takes place the several forces are balanced with the tube 62 in the position for optimum amperage. When the resistance in the electrolyte is increased or decreased as the result of any of the several variable factors, the core 154 and the tube 62 are automatically moved toward the left or toward the right to whatever extent is necessary to maintain the current at the optimum amperage.

Fig. 3 shows another alternative embodiment of the invention. The several parts 20, 22, 24, 26, 28 and 30 are or may be identical in construction with the parts shown in Fig. 1. A pipe 166 is provided which is similar to the pipe 32 and which serves to supply the emulsion E to the main cylindrical chamber near the right or entrance end thereof.

In lieu of the outlet pipe 34 connected with

the cylindrical chamber near the left end there is provided a similar outlet pipe or duct 168. In lieu of the steam siphon 36 there is provided an alternative suction means which is a reciprocating pump indicated generally at 169.

The pump 169 is or may be of standard construction and does not of itself constitute a part of the present invention. As shown, the pump has a lower chamber 170, an intermediate chamber 172 and an upper chamber 174. A central transverse wall 176 is provided in the chamber 172, a reciprocating piston 178 being movable through an opening in the said wall. Pivoted flaps 180 and 182 are provided at openings between the chambers 170 and 172 and respectively at the left and at the right of the wall 176, and pivoted flaps 184 and 186 are provided at openings between the chambers 172 and 174 respectively at the left and at the right of the wall 176.

As the piston 178 moves toward the right, the flaps 180 and 186 are opened, liquid being withdrawn from the chamber 170 into the chamber 172 and liquid being discharged from the chamber 172 into the chamber 174. As the piston 178 moves toward the left, the flaps 182 and 184 are opened, liquid being withdrawn from the chamber 170 into the chamber 172 and liquid being discharged from the chamber 172 into the chamber 174. A discharge pipe 188, similar to the pipe 46 is connected with the chamber 174, and liquid forced into the said chamber by the pump is discharged through the said pipe.

From the foregoing description it will be apparent that the pump 169 acts by suction to cause liquid to be withdrawn from the emulsion layer E, through the pipe 166, through the main cylindrical chamber, through the pipe or duct 168 and into the pump chamber 170. The pump forces liquid into the pump chamber 174 and through the discharge pipe 188.

In lieu of the inner electrode 56 there is provided an alternative inner electrode 190. The electrode 190 is specifically different from the electrode 56, but it is similar in that it has telescopically related portions and has different diameters at different positions along its length and in that it is adjustable as to length and area.

The inner electrode 190 comprises a centrally located metallic tube 192 which is closed at its right end by a cup-shaped metallic member 194. The tube 192 is held in place by insulating buttons 196, 196 which are connected with the tube 24 by screws 198, 198. The inner electrode preferably includes a ring 199 on the tube 192, this being similar in construction and in function to the ring 64 shown in Fig. 1.

The electrode 190 also comprises a member 200 which is a spring formed of a spirally wound strip of metal such as steel. The several convolutions of the spirally wound electrode member overlap each other and are therefore telescopically related. The outer end or portion of the metallic strip is mechanically and electrically connected with the tube 192 by screws 201 and is therefore fixed against longitudinal movement. The inner end or portion of the metallic strip is mechanically connected with a longitudinally movable insulating member 202. The spring member 196 is initially wound spirally as stated, but by means of the member 202 it may be drawn out or extended longitudinally or axially to the extent shown by full lines in Fig. 3. The portion of the strip or member 200 that is connected with the member 202 and the other portions of

the said member 200, except the said longitudinally fixed position, are movable longitudinally and telescopically with respect to each other and with respect to the said fixed portion.

5 Connected with the insulating member 202 is a rod 204 similar to the rod 96 shown in Fig. 1. Associated with the rod 204 are parts 98, 102, 104 and 106 which are or may be identical in construction with the parts shown in Fig. 1 and previously described. By means of the handle 104 the spring member 200 of the inner electrode may be extended as required. The full lines show the minimum extension and the dotted lines indicate the maximum extension. It will be understood that the spring member resists extension and tends to return to its shorter position.

A generally cylindrical member 206 of insulating material enters and fits the cup-shaped member 194, this member having a central chamber 208 therein which is open at the left to provide access to the transverse wall of the member 194. The tube 192 and the members 194 and 206 are connected with each other by screws 212.

20 25 A tubing connector 214 is threaded into a central aperture in the insulating member 206, a liquid-tight joint being provided. A longitudinal tube 216 is provided having a flared end, this tube being similar to the tube 76. The flared end of the tube 216 engages the connector 214, being held in place by a threaded sleeve 218. The tube extends through a central aperture in the end plate 28, a liquid-tight joint being provided by a gland 220. An insulated conductor wire 222 extends through the tube 216 and is connected at its inner end with the transverse wall of the cup-shaped member. The wire 222 corresponds in function to the wire 82 shown in Fig. 1.

30 35 For changing the thickness of the annular space between the outer face of the ring 199 and the inner face of the tube 22 a longitudinally movable annulus is provided which may be identical in construction and in manner of operation to the annulus 110 shown in Fig. 1.

40 45 The electrical system is or may be the same as that shown in Fig. 1 and previously described.

The manner of operation is generally similar to that described in connection with Fig. 1 and repetition of the description is unnecessary. It 50 will be seen that the length and area of the inner electrode is changed by increasing or decreasing the effective length of the spring member 200 instead of by bodily moving the tube 62. If desired, the movement of the spring member 200 may be controlled automatically as illustrated in Fig. 2.

55 Preferably a recirculation duct 224 is provided having a control valve 226 therein. The duct 224 is connected similarly to the duct 144 as shown in Fig. 1. If necessary, a means for supplying 60 a chemical may be connected with the duct 224. This comprises a container 148 and a valve or cock 150 as previously described.

65 70 As previously stated, it is frequently desirable to raise the temperature of the emulsion before it passes through the annular space between the electrodes. The pump 169 does not heat the liquid passing therethrough and it is therefore necessary to provide a separate means for heating the emulsion. As illustrated, a steam coil 228 is positioned within the supply pipe 166. An electric heating unit may be substituted for the steam coil. By means of the steam coil 228 or its equivalent, the emulsion is suitably heated before reaching the main chamber.

75 As an alternative to the heating means at 228

or in order to supplement the said heating means, a separate heating means may be provided in the recirculation duct 224. As shown, the liquid passes through a chamber 230 having a steam coil 232 therein. An electric heating unit may be substituted for the steam coil. When a heating means is provided at 232, the mixture delivered from the recirculation duct 224 is heated and the results are the same as those previously described in connection with the siphon 36 and the duct 144.

Heating means may be provided at 228 and also at 232, but either heating means is usually sufficient without the other and ordinarily only one of them is provided in any one installation.

The invention claimed is:

1. In an apparatus for treating an emulsion, the combination of an outer electrode comprising a metallic housing having a cylindrical chamber therein, an emulsion supply pipe communicating with the housing chamber near the entrance end thereof, an inner metallic electrode within the chamber of the outer electrode, insulating means for supporting the inner electrode in a central position within the chamber so as to provide an annular space between the outer and inner electrodes, an outlet pipe communicating with the said housing chamber near the opposite end thereof, a steam siphon connected with the outlet pipe and serving to withdraw liquid through the supply pipe and through the annular space in the chamber between the outer and inner electrodes and through the outlet pipe, means for connecting the outer and inner electrodes in an electric circuit to cause current to flow between the electrodes and through the liquid in the annular space between them, the said current serving to break the emulsion as it passes along the said annular space, and a recirculation duct connected at one end to said outlet pipe beyond said steam siphon and connected at the other end to the entrance portion of the cylindrical chamber, said steam siphon heating a portion of the treated liquid and forcing the heated portion through said recirculation duct so that the heated portion of the treated liquid is drawn with untreated liquid through the space between said electrodes.

2. In an apparatus for treating an emulsion, the combination of an outer electrode comprising a metallic housing having a cylindrical chamber therein, an emulsion supply pipe communicating with the housing chamber near the entrance end thereof, a metallic inner electrode within the chamber of the outer electrode and extending longitudinally thereof, insulating means for supporting the inner electrode in a central position within the chamber so as to provide an annular space between the outer and inner electrodes, an outlet pipe connected with the housing chamber near the opposite end thereof, means for causing a liquid which is initially an emulsion to move through the supply pipe and through the annular space between the outer and inner electrodes and through the outlet pipe, means for connecting the outer and inner electrodes in an electric circuit to cause current to flow between the electrodes and through the liquid in the annular space between them, the said current serving to break the emulsion as it passes along the said annular space, a conductive member within the outer electrode and adjacent the entrance end of the inner electrode which member is an annulus movable longitudinally along a face of one of said electrodes and having a conical face, and means for longitudinally moving said member for changing the thickness of the annular space

between the electrodes at the entrance end of the said space.

3. In an apparatus for treating an emulsion, the combination of an outer electrode comprising a metallic housing having a cylindrical chamber therein, an emulsion supply pipe communicating with the housing chamber near the entrance end thereof, a metallic inner electrode located within the chamber of the outer electrode and extending longitudinally thereof and having its maximum external diameter substantially less than the internal diameter of the outer electrode chamber, the said inner electrode having a cylindrical portion of uniform diameter near the entrance end of the housing and the said inner electrode including a structurally separate metallic ring connected to and surrounding the said cylindrical portion which ring has greater conductivity than the other portions of the inner electrode and has a diameter larger than that of any other portion of the inner electrode, insulating means for supporting the inner electrode in a central position within the chamber so as to provide an annular space between the outer and inner electrodes, an outlet pipe connected with the housing chamber near the opposite end thereof, means for causing a liquid which is initially an emulsion to move through the supply pipe and through the annular space between the outer and inner electrodes and through the outlet pipe, and means for connecting the outer and inner electrodes in an electric circuit to cause current to flow between the electrodes and through the liquid in the annular space between them, the said current serving to break the emulsion as it passes along the said annular space.

4. In an apparatus for treating an emulsion, the combination of an outer electrode comprising a metallic housing having a cylindrical chamber therein, an emulsion supply pipe communicating with the housing chamber near the entrance end thereof, a metallic inner electrode within the chamber of the outer electrode and extending longitudinally thereof which inner electrode comprises telescopically related portions at least one of which portions is fixed against longitudinal movement and another of which portions is movable longitudinally and telescopically with respect to the said fixed portion so as to change the length of the electrode, insulating means for supporting the inner electrode in a central position within the chamber of the outer electrode so as to provide an annular space between the outer and inner electrodes, means for longitudinally moving the said longitudinally movable portion of the inner electrode to change the length of the said electrode, an outlet pipe connected with the housing chamber near the opposite end thereof, means for causing a liquid which is initially an emulsion to move through the supply pipe and through the annular space between the outer and inner electrodes and through the outlet pipe, and means for connecting the outer and inner electrodes in an electric circuit to cause current to flow between the electrodes and through the liquid in the annular space between them, the said current serving to break the emulsion as it passes along the said annular space.

5. An apparatus as set forth in claim 4, wherein in the inner electrode has successively smaller diameters in the direction of liquid flow.

6. In an apparatus for treating an emulsion, the combination of an outer electrode comprising a metallic housing having a cylindrical chamber

therein, an emulsion supply pipe communicating with the housing chamber near the entrance end thereof, a metallic inner electrode within the chamber of the outer electrode and extending longitudinally thereof which inner electrode comprises a plurality of telescopic tubes, insulating means for supporting the inner electrode in a central position within the chamber of the outer electrode so as to provide an annular space between the outer and inner electrodes, means for longitudinally moving one tube of the inner electrode relatively to another tube thereof to change the length of the said inner electrode, an outlet pipe connected with the housing chamber near the opposite end thereof, means for causing a liquid which is initially an emulsion to move through the supply pipe and through the annular space between the outer and inner electrodes and through the outlet pipe, and means for connecting the outer and inner electrodes in an electric circuit to cause current to flow between the electrodes and through the liquid in the annular space between them, the said current serving to break the emulsion as it passes along the said annular space.

7. In an apparatus for treating an emulsion, the combination of an outer electrode comprising a metallic housing having a cylindrical chamber therein, an emulsion supply pipe communicating with the housing chamber near the entrance end thereof, a metallic inner electrode within the chamber of the outer electrode and extending longitudinally thereof which inner electrode comprises a plurality of telescopic tubes which are successively smaller in the direction of liquid flow, insulating means for supporting the inner electrode in a central position within the chamber of the outer electrode so as to provide an annular space between the outer and inner electrodes, means for longitudinally moving the smallest tube of the inner electrode relatively to the next adjacent tube to change the length of the said inner electrode, an outlet pipe connected with the housing chamber near the opposite end thereof, means for causing a liquid which is initially an emulsion to move through the supply pipe and through the annular space between the outer and inner electrodes and through the outlet pipe, and means for connecting the outer and inner electrodes in an electric circuit to cause current to flow between the electrodes and through the liquid in the annular space between them, the said current serving to break the emulsion as it passes along the said annular space.

8. In an apparatus for treating an emulsion, the combination of an outer electrode comprising a housing having a cylindrical chamber therein, an emulsion supply pipe communicating with the housing chamber near the entrance end thereof, a metallic inner electrode within the chamber of the outer electrode and extending longitudinally thereof which inner electrode comprises a plurality of telescopic tubes which are successively smaller in the direction of liquid flow, insulating means for supporting the inner electrode in a central position within the chamber of the outer electrode so as to provide an annular space between the outer and inner electrodes, a spring connected with the smallest tube of the inner electrode for longitudinally moving the said tube in the direction to decrease the length of the said inner electrode, means for longitudinally moving the said smallest tube of the inner electrode in opposition to the said spring to increase the length of the said inner electrode, an outlet pipe con-

nected with the housing chamber near the opposite end thereof, means for causing a liquid which is initially an emulsion to move through the supply pipe and through the annular space between the outer and inner electrodes and through the outlet pipe, and means for connecting the outer and inner electrodes in an electric circuit to cause current to flow between the electrodes and through the liquid in the annular space between them, the said current serving to break the emulsion as it passes along the said annular space.

9. In an apparatus for treating an emulsion, the combination of an outer electrode comprising a metallic housing having a cylindrical chamber therein, an emulsion supply pipe communicating with the housing chamber near the entrance end thereof, a metallic inner electrode within the chamber of the outer electrode and extending longitudinally thereof which inner electrode comprises an extensible spirally coiled spring strip having its convolutions overlapping each other and telescopically related, the said spring strip having a portion at one end thereof fixed against longitudinal movement and having other portions thereof longitudinally movable telescopically relatively to the said fixed portion, insulating means for supporting the inner electrode in a central position within the chamber of the outer electrode so as to provide an annular space between the outer and inner electrodes, means connected with the coiled spring strip at the end thereof opposite the said fixed portion for longitudinally and telescopically moving the longitudinally movable portions of the said strip so as to change the amount of extension of the strip and so as to thereby change the length of the said inner electrode, an outlet pipe connected with the housing chamber near the opposite end thereof, means for causing a liquid which is initially an emulsion to move through the supply pipe and through the annular space between the outer and inner electrodes and through the outlet pipe, and means for connecting the outer and inner electrodes in an electric circuit to cause current to flow between the electrodes and through the liquid in the annular space between them, the said current serving to break the emulsion as it passes along the said annular space.
10. In an apparatus for treating an emulsion, the combination of an outer electrode comprising a metallic housing having a cylindrical chamber therein, an emulsion supply pipe communicating with the housing chamber near the entrance end thereof, a metallic inner electrode within the chamber of the outer electrode and extending longitudinally thereof which inner electrode comprises a portion fixed against longitudinal movement and another portion longitudinally movable with respect to the said fixed portion to change the length of the said electrode, insulating means for supporting the inner electrode in a central position within the chamber of the outer electrode so as to provide an annular space between the outer and inner electrodes, an outlet pipe connected with the housing chamber near the opposite end thereof, means for causing a liquid which is initially an emulsion to move through the supply pipe and through the annular space between the outer and inner electrodes and through the outlet pipe, means for connecting the outer and inner electrodes in an electric circuit to cause current to flow between the electrodes and through the liquid in the annular space between them, the said current serving to break the emul-

15

sion as it passes along the said annular space, and means controlled by the current in the circuit for longitudinally moving the said longitudinally movable portion of the inner electrode to change the length of the said electrode.
